[57] CLAIM

The ornamental design for a lift rack with divider system, as shown and described.

DESCRIPTION

FIG. 1 is a perspective view of a lift rack with divider system showing my new design;

FIG. 2 is a front view thereof;

FIG. 3 is a left side view, right side being a mirror image thereof;

FIG. 4 is a rear view thereof;

FIG. 5 is a top view thereof; and,

FIG. 6 is a bottom view thereof.

The openings shown in FIGS. 1, 2, 4, 5 & 6 are partially shown and are understood to repeat uniformly across the circumscribed area.
